(57) **CLAIM**

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a left side view thereof;

FIG. 5 is a right-side view thereof;

FIG. 6 is a top view thereof;

FIG. 7 is a bottom view thereof;

FIG. 8 is a perspective view of the beverage container, shown in an open position; and,

FIG. 9 is another perspective view, showing the beverage container in a state of use with a straw.

The evenly spaced broken lines depict portions of the beverage container that form no part of the claimed design. The dot-dot-dash broken lines in the drawings depict environmental structure, specifically the straw in FIG. 9, that form no part of the claimed design. The dot-dash broken lines in FIG. 7 show boundary and form no part of the claimed design.
